CLAIM

The ornamental design for a display screen with graphical user interface as shown and described.

DESCRIPTION

FIG. 1 is a front view of a display screen with graphical user interface showing our new design; and,

FIG. 2 is an enlarged view of the region as defined by box 2 as shown in FIG. 1.

The uneven-length broken lines defining box 2 is for identification and enlargement purposes only and forms no part of the claimed design. The even-length broken lines at the perimeter of the figure illustrates the display screen and the remaining broken lines illustrate portions of the graphical user interface. None of the broken lines form part of the claimed design.
